(57) **CLAIM**

(**) Term: **14 Years**

The ornamental design for a universal furnace igniter bracket set, as shown and described.

DESCRIPTION

FIG. 1 is a perspective view of a universal furnace igniter bracket set comprised of small and large adapter brackets showing our new design;

FIG. 2 is a top plan view thereof;

FIG. 3 is a side elevation view thereof;

FIG. 4 is a bottom plan view thereof;

FIG. 5 is a front elevation view thereof; and,

FIG. 6 is a rear elevation view of the small adapter bracket. The elements of the claimed design are shown detached for clarity of illustration.
